UNITED STATES PATENT OFFICE.

MAX SLOANE, OF BROOKLYN, NEW YORK.

DESIGN FOR A HANDBAG-FRAME.

57,868.

Specification for Design.

Patented May 10, 1921.

Application filed August 10, 1920. Serial No. 402,703. Term of patent 7 years.

To all whom it may concern:

Be it known that I, MAX SLOANE, a citizen of Russia, and a resident of the city of New York, borough of Brooklyn, in the county of Kings and State of New York, United States of America, have invented a new, original, and ornamental Design for a Handbag-Frame.

Reference is to be had to the accompanying drawings in which—

Fig. 2 is a plan view thereof.

I claim:—

The ornamental design for a handbag frame, as shown.

MAX SLOANE.
